UNITED STATES PATENT OFFICE.

EDWARD C. EBERTS, OF JEFFERSONVILLE, INDIANA.

STOCK DIVIDER.

1,417,045.

Specification of Letters Patent. Patented May 23, 1922.

Application filed July 19, 1921. Serial No. 435,937.

To all whom it may concern:

Be it known that I, EDWARD C. EBERTS, a citizen of the United States, and resident of Jeffersonville, in the county of Clark and State of Indiana, have invented certain new and useful Improvements in Stock Dividers, of which the following is a specification.

My present invention relates to improvements in stock dividers of the type in which 10 a supply of pulverous or granular material is divided into certain proportionate parts.

It is designed more especially for use in connection with the feed of material, such for example as grain or grain products to 15 grinding mills, but is advantageous for many other purposes, as for example in connection with the feed of material to sifter sections, reels, purifiers and in fact any machine or apparatus where division is necessary or desirable.

The invention aims to provide a form of apparatus which will accurately divide the material under any and all conditions of material and variations in the supply or flow 25 thereof.

The invention further aims to provide apparatus which will be of simple and durable construction, and require but a negligible amount of power for operation.

30 A further object is to provide a construction adaptable to divide the stock into any desired proportionate parts, and into any desired number of parts.

With these and other objects in view, the 35 invention includes the novel features of construction and arrangement and combination of parts hereinafter described and particularly defined in the appended claims.

An embodiment of the invention is illustrated in the accompanying drawings in which

Figure 1 is a central longitudinal section through a stock divider according to my invention.

45 Fig. 2 is a transverse section on line 2—2 of Fig. 1.

Fig. 3 is a perspective view of the form of divider wheel shown in Fig. 1.

Fig. 4 is a similar view of a modification, 50 and

Fig. 5 is a similar view of a further modification.

Referring by reference characters to these

drawings, the numeral 1 indicates a suitable frame or housing having a substantially central feed opening 1^a in the top thereof, into which the material to be divided may be fed in any suitable manner. Within the housing is a substantially cylindrical casing 2 which may be conveniently formed of sheet metal 60 bent up into substantially cylindrical or trough form.

When the housing is of construction rendering this desirable the casing 2 may have wings 2^a which are projected into and secured 65 to the walls of the feed opening, thereby serving in part as means for connecting the casing to the housing or frame.

The casing or trough is open at opposite ends to permit free discharge of material 70 therefrom.

Located in the casing and centrally beneath the feed opening is a divider wheel 3 mounted on a shaft 4 journaled in the end walls of the housing, which shaft is designed 75 to be driven in any suitable manner.

This wheel has a plurality of segmental pockets or deflecting portions which are alternately arranged and which are designed to register successively with the feed opening, and which have reversely inclined deflecting walls designed to deflect the material alternately towards opposite ends of the casing, the wheel itself being of solid or im-perforate construction, so that it separates 85 the casing into two compartments.

In my preferred construction the wheel is composed of two segments, 3^a and 3^b of sheet metal (each being practically the segment of a truncated cone) reversely placed relatively to each other and having a central disc portion 3^c joined to the truncated edges which serves for connection to a hub 4^a having a suitable means for attachment to the shaft 4.

The adjacent edges of the segmental portions are connected by substantially trans-verse walls 3^d, i. e., walls which lie (preferably) in a plane, or planes, coinciding with the axis of the wheel.

In the form shown in Figs. 1 to 3 inclusive, the wheel is designed to divide the stock supplied to the feed opening into exactly equal parts, and to this end the segmental portions are of equal area, or in other words 105 are of duplicate form but reverse arrange-

ment, and it will readily be seen that as the wheel is rotated at uniform speed the stock will be deflected first towards one discharge end of the casing and then towards the opposite end in exactly equal proportions.

It will be readily understood that this proportion may be varied to any desired extent by varying the proportions of the segmental portions.

10 As illustrative of this, I have shown in Fig. 4, a wheel adapted to divide the stock in the proportions of 2 to 1, and to this end make the segment 3^e twice the size of the segment 3^f , but this is illustrative only, and 15 any desired proportion may be secured by proper ratio of segment surfaces.

If desired deflector wings 3^h may be applied to the wheels to assist in the projection of the material into the discharge passages 20 of the casing or trough.

In case it is desired to divide the material into four equal parts, I may use a divider such as shown in Figs. 1 and 2, to first divide it into two equal parts and have such 25 divider discharge at its opposite ends into two similar dividers which would in turn sub-divide each stream into two equal parts.

Similarly if a division into three parts is desired I may use a divider having a wheel 30 such as shown in Fig. 4, dividing the stock in the 2 to 1 proportion, and again divide the larger stream into two parts by the divider of Figs. 1 and 2, giving as the final 35 result three equal divisions.

35 In the embodiment shown in Fig. 5 the wheel is provided with four pockets and is formed from a single blank of sheet metal, the edges of the segmental portions being turned towards each other and overlapped 40 and secured together to form the division 45 walls as indicated at 3^i .

In this form I show deflector wings 3^k extending diagonally across the outer portions of the pockets.

45 A divider such as above described is simple and durable, can be run with a negligible amount of power, and will always divide the stock into correct proportionate parts irrespective of the character or rapidity of feed

of material thereto, and cannot become 50 choked in use.

Having thus described my invention what I claim is—

1. A stock divider comprising a stationary cylindrical casing, having an intermediate feed opening at the top, and discharge passages below and on opposite sides of said feed opening, and a divider wheel rotatably mounted in said casing below said feed opening and having segmental receiving chambers disposed on opposite sides of the plane of the axis of the opening and designed to communicate alternately with said feed opening and to discharge the material alternately into the discharge passages. 65

2. A stock divider comprising a cylindrical casing having an intermediate feed opening and discharge passages on opposite sides of said feed opening and a divider wheel rotatably mounted in said casing and having segmental receiving chambers designed to communicate alternately with said feed opening and to discharge the material alternately into the discharge passages, said receiving chambers having a relative circumferential extension proportionate to the desired proportions of stock. 75

3. A stock divider comprising a casing having a feed opening and discharge passages, and a divider wheel rotatably mounted in the casing centrally of said feed opening and having segmental portions deflected alternately towards opposite sides of the feed opening, said deflected portions having their adjacent edges connected by angularly disposed walls. 85

4. A stock divider comprising a cylindrical casing having an intermediate feed opening and discharge passages on opposite sides of said feed opening and a divider wheel 90 rotatably mounted in said casing and having segmental receiving chambers designed to communicate alternately with said feed opening and to discharge the material alternately into the discharge passages, said deflector wheel having deflector wings. 95

In testimony whereof I affix my signature.

EDWARD C. EBERTS.
